(57) **CLAIM**

The ornamental design for a palatal expansion appliance, as shown and described.

DESCRIPTION

FIG. 1 is a top perspective view of a palatal expansion appliance illustrating an embodiment of my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 depicts the alternate position thereof.

The contrast in shading (line shading) represents a contrast in appearance only and does not represent any particular color, material, texture, or finish.
